UNITED STATES PATENT OFFICE.

JOHN E. DAWSEY, OF CONWAY, SOUTH CAROLINA.

TIMEPIECE.

1,153,038.

Specification of Letters Patent. Patented Sept. 7, 1915.

Application filed November 4, 1914. Serial No. 870,284.

To all whom it may concern:

Be it known that I, JOHN E. DAWSEY, a citizen of the United States, residing at Conway, in the county of Horry and State of South Carolina, have invented new and useful Improvements in Timepieces, of which the following is a specification.

This invention relates to time pieces, the object in view being to produce a time piece in which the mechanism is of such a character as to provide for a step by step movement of a series of time indicating disks mounted in overlapping relation to each other so as to secure a compact display of the characters thereon which indicate the time, thus doing away with the usual hands such as the hour, minute and second hands now commonly employed in watches, clocks and the like.

With the above and other objects in view, the invention consists in the novel construction, combination and arrangement of parts, as herein described, illustrated and claimed.

In the accompanying drawings: Figure 1 is a front face view of a watch embodying the present invention showing the orifices for displaying the time indicating characters. Fig. 2 is an enlarged longitudinal section taken in front of the time indicating disks. Fig. 3 is a similar section taken in rear of the time indicating disks and illustrating the step by step mechanism. Fig. 4 is a similar view with the large minute wheel omitted and showing the minute arbor in section. Fig. 5 is an enlarged fragmentary view showing a portion of the minute wheel, and the pinion and escapement wheel associated therewith, also the escapement lever.

For the purpose of carrying out the present invention, the case 1 of the time piece is provided with an orifice or observation opening 2 of sufficient size only to display, in the preferred embodiment of this invention, numerals to designate the time. In addition thereto, the case of the time piece is provided with another smaller orifice 3 through which a sufficient portion of the second disk is visible to indicate the seconds in connection with the time in hours and minutes.

4 designates the minute arbor which makes a complete revolution in one hour. Fast on the minute arbor 4 is a large gear or minute wheel 5 provided with escapement teeth 6 or, in other words, teeth having substantially

parallel front and rear faces and inclined extremities. Fast on the same arbor 4 is a pinion 7 provided with six teeth and another pinion 8 having but a single tooth projecting therefrom, the purpose of which will appear.

The wheel 5 meshes with and drives a spur gear 9 having the ordinary rounded spur teeth as best illustrated in Fig. 5. This wheel 9 is mounted on an arbor 10 and on the same arbor there is mounted an escapement wheel 11 having ratchet shaped teeth which are adapted to be engaged by the arm 12 of an escapement lever designated generally at A, the other arm 13 of said lever being adapted to engage the teeth 6 of the wheel 5. The spur gear 9 and escapement wheel 11 have a limited relative rotative movement on concentric axes which is effected by mounting one of said wheels loosely on the arbor 10 and connecting the gear and wheel by means of a coiled spring 14 one extremity of which is secured to one of said wheels at the point 15 and the other extremity of which is secured either to the spur gear 9 or the arbor 10 as may be found most convenient. The spring 14 admits of one of said wheels turning relatively to the other and the extent of movement is limited by co-operating stops 16 and 17 one of which is on the spur gear 9 and the other on the escapement wheel 11, said stops being on the adjacent faces of said wheels.

18 designates a spring bearing against the arm 13 of the escapement lever to move the same toward the wheel 5, the beveled extremities of the teeth 6 serving to move the escapement lever in the opposite direction to release the wheel 12. A secondary minute wheel or time indicating disk 19 is mounted on the arbor 10 and bears a fixed relation to the escapement wheel 11 so as to rotate therewith. It will now be seen that the wheel 5 drives the pinion 9 while the wheel 11 is held back by the arm 12 of the escapement lever A. At a certain point, however, the teeth 6 of the wheel 5 act on the escapement lever to release the wheel 11 which is thereupon quickly turned a distance governed by the distance between the stops 16 and 17. This has the effect of quickly turning the disk 19 so as to bring the next indicating character 20 thereof in line with the opening 2 in the case of the time piece.

In addition to the secondary minute disk 19, I provide a primary minute disk 21, an

hour disk 22 and a second disk 23. The hour disk 22 is actuated by a dog or lever 24 which is fulcrumed at 25 on the frame of the movement and provided with an arm 26 adapted to be struck by the single tooth of the pinion 8. The other extremity of said lever or dog cooperates with a ratchet shaped wheel 27 having a fixed relation to the hour disk 22. The wheel 27 has 12 teeth and therefore in each complete revolution of the minute arbor 4, the wheel 27 is advanced the distance of one tooth which is equal to the distance between the time indicating characters on said disk as shown in Fig. 2. In like manner the primary minute disk 21 has mounted in fixed relation thereto a pinion 28 having six ratchet shaped teeth thereon adapted to be successively operated upon by the adjacent extremity of another dog or lever 29 which is fulcrumed at 30 on the movement and provided with an arm 31 adapted to be successively struck by the six teeth of the pinion 7. Detents 32 and 33 are used in conjunction with the wheels 27 and 28, respectively, for the purpose of retaining the disks 21 and 22 against movement until they are acted upon by the mechanism just described. Springs 34 and 35 act against the dogs or levers 24 and 29, respectively, to hold the same against stops 36 and 37 shown in the form of pins projecting from the frame of the movement. The second indicating disk 23 is mounted fast on the second arbor 39 and the indicating characters thereof are displayed through the smaller orifice 3 in the case of the time piece.

40 designates the arbor of the primary minute disk 21 and 41 designates the arbor of the hour disk 22.

40 From the foregoing description taken in connection with the accompanying drawings, the operation of the mechanism will now be understood. As the wheel 5 is driven by the minute arbor 4, the teeth thereof drive the pinion 9 and also actuate the escapement lever A with the result that the wheel 9 is driven steadily while the escapement wheel 11 is held back by the lever A. At the proper moment, the escapement lever A is acted upon by the beveled extremities of the teeth 6, thereby releasing the wheel 11 which carries the secondary minute disk 19. Therefore a quick partial turning movement of the disk 19 is effected, bringing the next in-

dicating character before the orifice 2. In like manner the teeth of the pinions 7 and 8 act on the dogs or levers 24 and 29 and impart a step by step movement to each of the wheels 27 and 28 thereby turning the disks 21 and 22 in a corresponding manner, that is to say with a step by step movement. This causes the characters to be quickly presented before the orifice 2 and avoids any confusion which would otherwise arise if the time indicating disks were driven at uniform speed. The second indicating disk 23 revolves so rapidly that it is not considered necessary to drive the last named disk with a step by step movement, the designating characters appearing almost continuously under the observation orifice 3.

It will of course be understood that the mechanism hereinabove described is applicable to all kinds of time pieces including watches and clocks. It will also be understood that the invention is susceptible of various changes in the form, proportion and minor details of construction which may be resorted to without departing from the principle or sacrificing any of the advantages of the invention.

What I claim is:—

In a time piece, the combination with the minute arbor, of a series of overlapping time indicating disks, a gear fast on said arbor and provided with escapement teeth, a spur pinion driven thereby, an arbor for said pinion, an escapement wheel on said pinion arbor, and means admitting of a limited relative rotative movement of said pinion and escapement wheel, whereby the spur pinion is constantly revolved and the escapement wheel is operated intermittently, said means embodying a spring connecting said pinion and escapement wheel and acting to quickly advance the escapement wheel when the latter is released by the escapement lever, and an escapement lever one arm of which cooperates with the minute gear and the other arm of which cooperates with said escapement wheel.

In testimony whereof I affix my signature in presence of two witnesses.

JOHN E. DAWSEY.
